UNITED STATES PATENT OFFICE.

LEONARD D. MORRIS, OF CHICAGO, ILLINOIS.

ELECTROMAGNETIC ORGAN-ACTION.

1,282,275.

Specification of Letters Patent.

Patented Oct. 22, 1918.

Application filed September 13, 1917. Serial No. 191,274.

To all whom it may concern:

Be it known that I, LEONARD D. MORRIS, a citizen of the United States, residing at Chicago, in the county of Cook and State of Illinois, have invented certain new and useful Improvements in Electromagnetic Organ-Actions, of which the following is a specification.

The essential object of this invention is to provide a certain new and useful improvement in actions for organs of the electromagnetic type, and the invention embodies a coil adapted to be energized upon depression of one of the keys—either manual or pedal—15 and means actuated by the coil controlling the passage of air from the bellows or blower into the pipe or pipes.

In the drawings, Figure 1 is a vertical sectional view of so much of an organ as is necessary to depict the invention; Fig 2 is a view looking upwardly in Fig. 1 showing the armature which is attracted by the coil and the member upon which said armature is carried; and Fig. 3 is a view of the 25 parts shown in Fig. 2, Figs. 2 and 3 being at right angles to each other.

The base or board 1 is apertured at 2 and one of the organ pipes (not shown) is either fitted into aperture 2 or in suitable connection therewith so that the compressed air within the wind chest 3 may pass in the direction of the arrow A. The wind chest 3 is shown as being substantially rectangular in section and may be formed of the board 35 1 together with other boards or walls 4 and 5. The devices forming the subject matter of the herein described invention are intended to open and close the aperture 2 and are preferably retained within the chamber 3.

A bracket 6 made of metal or other suitable material is secured by screws to the perforated baseboard 1. Said bracket 6 bears an arm 7 which lies in a plane substantially parallel to the base-board 1, and the coil 8 is bolted or screwed at 9 to arm 7. Inside of the coil 8 is a core 10 which is magnetized when the coil 8 is energized, and suitable wires (not shown) extend from the 50 coil 8 to the appropriate key of the instrument, the circuit being so arranged that depression of the appropriate key closes the circuit through the coil 8 and magnetizes the core 10.

An L-shaped piece 11 preferably formed of relatively thin spring steel is riveted or

secured at 12 to the bracket 6. Said spring-like member 11 extends transversely across the coil 8 and substantially perpendicular to the soft iron core 10. An armature 14 made of soft iron is riveted at 15 to the spring 11, which armature 15 bears a layer of felt 16 so as to prevent impact of the metal armature 14 upon the metal core 10, for the noise that would be permitted were 65 these two hard parts to contact would be highly objectionable in any organ. At its free end the spring 11 carries a disk 17 made of felt or other soft material and opening inwardly of the wind chest, which disk 70 17 normally closes the aperture 2, being pushed into contact with the perforated base-board 1 because of the action of the spring 11. When the coil 8 is energized and the core 10 magnetized, said core attracts 75 the armature 14 and thus pulls the free end of the spring 11 downwardly in Fig. 1, carrying the valve-like disk 17 away from the lower mouth of the aperture 2, which opening of the aperture 2 permits the air from 80 the chamber 3 to pass upwardly in the direction of the arrow A and sound the pipe which connects with the aperture 2.

In order to regulate the normal position of the arm 11 a screw 18 is provided, the 85 head of which engages the spring 11 on the same side of said spring as the armature 14. The shank of the screw passes through the perforation 19 in the spring 11 and is received within a suitable taphole provided 90 therefor either in the bracket 6 or the base-board 1.

It is obvious that sundry changes in the details of construction and arrangement of parts may be made without departing from 95 the scope of the invention.

I claim as my invention:

1. A device of the character described comprising a core, an armature located to be attracted thereby, a spring upon which 100 said armature is carried, a baseboard having a perforation, a valve adapted to close said perforation, secured near the free end of said spring and normally closed thereby, and means for adjusting the valve closing 105 pressure of said spring.

2. A device of the character described comprising a perforated base-board, a bracket depending therefrom, a core supported by the bracket, an L-shaped spring 110 having one end secured to said bracket and extending substantially at right angles to

said core, a valve carried upon the free end of said spring, an armature also carried upon said spring, and a screw extending from said spring to said perforated base-plate and adapted to regulate the tension of said spring.

3. In a device of the character described comprising a perforated base-board, a bracket depending therefrom, a core supported by the bracket, an L-shaped spring having one end secured to said bracket and extending substantially at right angles to said core, a valve carried upon the free end of said spring, an armature also carried upon said spring, a screw extending from said

spring to said perforated base-plate and adapted to regulate the tension of said spring, and a layer of sound absorbing, non-magnetic material intermediate the armature and the core.

20

4. An electromagnetic organ valve, comprising an electromagnet, a rigid support therefor, a leaf spring fixed by one end to said support and having its free end located to be attracted by the electromagnet, a valve 25 carried on the free end of the spring, and a screw threaded into the support and connected to the free end of the spring.

In testimony whereof I affix my signature.
LEONARD D. MORRIS.
